UNITED STATES PATENT OFFICE.

MORRIS KLINE, OF CLEVELAND, OHIO.

ADVERTISING CHANGE-TRAY.

1,389,365.

Specification of Letters Patent. Patented Aug. 30, 1921.

Application filed August 5, 1918. Serial No. 248,273.

To all whom it may concern:

- Be it known that I, MORRIS KLINE, a citizen of the United States, residing at Cleveland in the county of Cuyahoga and State of Ohio, have invented a certain new and useful Improvement in Advertising Change-Trays, of which the following is a full, clear, and exact description, reference being had to the accompanying drawings.
- 10 This invention relates to an advertising device in the form of a change tray for use on the counters of cigar stands, cashiers' desks of lunch rooms and restaurants, and in any or all similar places.
- 15 The purpose of the invention, broadly speaking, is to provide a change tray associated with an advertisement which is revealed, or at least rendered more conspicuous or attractive, upon the deposit of one 20 or more coins in the change tray.
- More limitedly, the purpose is to provide a change tray bearing an advertisement and incorporating an illuminating device and controlling means therefor which is actuated 25 by the placing of a coin or coins in the tray, so that the illuminating device will become effective to reveal or attract attention to the advertisement.
- Further objects are to provide an apparatus of the foregoing nature that is comparatively simple of construction and consequently cheap of production and durable; and which is highly efficient as an advertising medium, and thoroughly convenient of 30 use as a change tray.
- In the accompanying drawing I have illustrated an embodiment of my invention through which the foregoing objects, and others which will become apparent as this 35 description proceeds, are attained.
- In the drawing, Figure 1 is a perspective view of a change tray incorporating my invention; Fig. 2 is a vertical section through the change tray at right angles to the pivotal axis of the tray; Fig. 3 is a plan of the base; and Fig. 4 an inverted plane of the change tray.
- In the present preferred embodiment of my invention I employ a base carrying an 40 electrical illuminating device and a switch for controlling the same, and I pivotally support above the base a shell incorporating the change tray, the shell being slightly overbalanced in one direction by the weight of 45 a coin, and acting, when so rocked or overbalanced, to close the switch. While in the
- present instance I use an opaque glass for the shell and apply to its inner surface an advertisement which is revealed through the glass when the illuminating device is 50 lighted, it will be understood that I do not limit myself to such an arrangement, it being clearly within the scope of my invention to make the shell of any desired material, having an opaque section for the advertisement; or in fact I may modify the embodiment of my invention to any extent desired so long as I restrict myself to the spirit of 55 the claims.
- As shown in the drawing, the base 1 is in 60 the form of a shallow circular pan having knife edge bearing elements 2 rising from opposed sides thereof. An incandescent lamp 3 is supported within the base, by a socket 4; and a two-strand electrical conductor 5 is led in through the side of the base and has one of its strands connected to a terminal of the socket 4 while its other strand is electrically connected to one side of 65 a switch 8; the opposite side of the switch having electrical connection with the remaining terminal of the socket 4. In the present instance the switch comprises a bridging element 9, carried by the coin tray, and the ends of which are adapted to be 70 dipped into the mercury wells 10, supported by the base, when the tray is depressed under the weight of one or more coins.
- The change tray proper, designated 12, is 75 formed by a depression in the shell 13, the shell extending down over and about the base 1 and having bearing sockets 14 which rest upon the knife edge bearing elements 2. The depending side wall of the shell remote from the coin tray is made thick 80 enough at one point to contain a well 16 into which suitable weight material 17, such as shot, may be confined by a closure 18 the same being shown, in the present instance, as an ordinary cork stopper. This arrangement provides a cheap yet very effective adjustable weight for attaining a proper balancing of the tray upon the bearing elements 2 so as to cause its opposite side to be 85 depressed, by the introduction of a coin into the change tray, sufficiently to immerse the ends of the bridging element 9 into the mercury in wells 10 and close the circuit of the lamp 3. Since the advertisement is applied to the inner sides of the opaque glass shell, 90 it becomes revealed only when the lamp is lighted, thus making it more attractive and 95

creating more comment than if it were at all times displayed.

Having thus described my invention, what I claim is:—

- 5 1. In a device of the character set forth, the combination of a base, a change tray pivotally supported thereby, and bearing an advertisement, an electrical illuminating device carried by the base for lighting the advertisement, a switch supported by the base and adapted to be closed by the tilting of the change tray under the weight of a coin, and a circuit including the illuminating device and switch. 35
- 10 2. In a device of the character set forth, the combination of a base, a shell pivotally supported thereby and bearing an advertisement, the shell incorporating a change tray on one side of its pivotal axis, an adjustable weight carried by the shell on the other side of its pivotal axis, an electrical illuminating device for the advertisement, a switch adapted to be closed by the tilting of the shell under the weight of a coin in the change tray, and an electric circuit including the switch and illuminating device. 40
- 15 3. In a device of the character set forth, the combination of a base, a shell, pivotally supported above the base and extending downward about and practically concealing 45

the base, the shell bearing an advertisement and incorporating a change tray, an illuminating device carried by the base for lighting the advertisement, a switch arranged to be closed by the tilting of the shell under the weight of a coin within the change tray, and an electric circuit including the illuminating device and switch.

4. In a device of the character set forth, the combination of a base, a shell of translucent material pivotally supported by the base and incorporating a change tray on one side of its pivotal axis, the inner surface of the shell bearing an advertisement, an illuminating device within the shell, and controlling means therefor arranged to be actuated by the tilting of the shell under the weight of a coin within the change tray.

5. In a device of the character set forth, the combination of a base incorporating a translucent advertisement and a change tray, an electric illuminating device for lighting the advertisement and concealed by the base, and a normally open electric circuit including the illuminating device and arranged to be closed by the placing of a coin in the change tray. 55

In testimony whereof, I hereunto affix my signature.

MORRIS KLINE.
